CLAIM

The ornamental design for a charger for a portable radio telephone, as shown and described.

DESCRIPTION

FIG. 1 is a front, top and right side perspective view of a charger for a portable radio telephone showing my new design;

FIG. 2 is a front elevational view thereof;

FIG. 3 is a top plan elevational view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a sectional view taken on line VIII—VIII in FIG. 2 with a interior construction omitted; and

FIG. 9 is a left side elevational view thereof depicting in broken lines a portable radio telephone positioned therein for incurring a charge.

The broken line showing of a portable radio telephone is for illustrative purposes only and forms no part of the claimed design.
